(57) **CLAIM**

The ornamental design for a hand grip for a mop, as shown and described.

DESCRIPTION

FIG. 1 is a perspective view of a hand grip for a mop in accordance with the present invention; and,

FIG. 2 is an enlarged side view of the hand grip of the mop of FIG. 1.

The broken line showing of the remainder of the mop in FIG. 1 is for illustrative purposes only and forms no part of the claimed design.
